COMBINED AUTOMOBILE DASHBOARD AND STEERING WHEEL TOY

Albert Stubbmann, Franklin Lakes, N.J., assignor to
Kohner Bros., Inc., East Paterson, N.J.

Filed Feb. 12, 1970, Ser. No. 21,407

Term of patent 14 years

Int. Cl. D21—02

U.S. Cl. D34—15

FIG. 1

FIG. 2

FIG. 3

FIG. 1 is a front isometric view of the combined automobile dashboard and steering wheel toy showing my new design;

FIG. 2 is a rear perspective view thereof; and

FIG. 3 is a left side elevational view of FIG. 1.

I claim:

The ornamental design for combined automobile dashboard and steering wheel toy, substantially as shown.
